(57) **CLAIM**

The ornamental design for a laser level with level body, as shown and described.

DESCRIPTION

FIG. 1 is a perspective front view of a laser level with level body showing my new design;

FIG. 2 is a side view thereof;

FIG. 3 is another side view thereof;

FIG. 4 is a rear view thereof;

FIG. 5 is a bottom view thereof; and,

FIG. 6 is a perspective top view, with the level body shown in a different position, of a laser level with level body showing my new design.
